COVERED FOOD DISH OR THE LIKE

Thomas M. Britt, Red Bank, N.J., assignor to Owens-Illinois, Inc., Toledo, Ohio, a corporation of Ohio

Filed June 6, 1969, Ser. No. 17,552

Term of patent 14 years

Int. Cl. D9—04

U.S. Cl. D9—182

FIG. 4

FIG. 5

FIG. 3

FIG. 7

FIG. 6

FIG. 8

FIG. 1 is a perspective view of a covered food dish showing my new design in its closed position;

FIG. 2 is a perspective view of a covered food dish in its open position;

FIG. 3 is a top plan view;

FIG. 4 is a front elevational view;

FIG. 5 is a right side elevational view;

FIG. 6 is a bottom plan view;

FIG. 7 is a rear elevational view;

FIG. 8 is an enlarged fragmentary cross-sectional view taken along line 8-8 of FIG. 6.

I claim:

The ornamental design for a covered food dish or the like, substantially as shown.
